A. A. BRIGHAM

THREAD SPLICING MACHINE

Filed April 15, 1922

Patented June 26, 1923.

1,459,875

UNITED STATES PATENT OFFICE.

ARTHUR A. BRIGHAM, OF BOSTON, MASSACHUSETTS.

THREAD-SPlicing MACHINE.

Application filed April 15, 1922. Serial No. 552,915.

To all whom it may concern:

Be it known that I, ARTHUR A. BRIGHAM, a citizen of the United States, residing at Boston, in the county of Suffolk and State 5 of Massachusetts, have invented certain new and useful Improvements in Thread-Splicing Machines, of which the following is a specification.

This invention relates to thread splicing 10 machines, more especially machines of the character disclosed in my Patent No. 1,239,560 dated September 11, 1917.

It is the chief object of the invention to improve the machine shown in my patent 15 aforesaid with a view to increasing the range of work which it is adapted to handle, avoiding any possibility of injury to the thread during the thread splicing operation, facilitating the steps necessary to perform 20 this operation, and generally perfecting the machine. The invention is concerned especially with the construction of the twister heads and with the devices for holding the strands of the untwisted threads preparatory 25 to associating them in the making of the splice.

The nature of the invention will be readily understood from the following description when read in connection with the accompanying drawings, and the novel features 30 will be particularly pointed out in the appended claims.

In the drawings,

Figure 1 is a plan view of the machine 35 shown in my prior patent, above designated, but modified in accordance with the present invention;

Fig. 2 is a perspective view of the left-hand twister head of the machine shown in 40 Fig. 1;

Fig. 3 is a longitudinal cross sectional view through a portion of the strand holding device; and

Fig. 4 is a cross sectional view through 45 one end of a twister head.

For a complete description of the construction and operation of the machine shown in the drawings, reference should be made to my prior patent, above designated. 50 It is sufficient for the present purposes to describe the general organization of this machine very briefly. The machine comprises two twister heads, designated at A and B, respectively, both mounted on a base plate 2, substantially in alignment with each other. The cops or spools holding the two lengths

of thread to be spliced together are supported on pins 4 and 5, mounted, respectively, in brackets 6 and 7, each carried by a pair of rods which are slidably mounted in the lower part of the base 2 so that the brackets can be adjusted toward and from the base. The threads unwound from these spools are designated at *a* and *b*, respectively. 60

Each twister head comprises a shaft 10, Figs. 2 and 4, having a thread receiving slot or groove 11 formed longitudinally therein of a depth to extend substantially to the axis of rotation of the shaft. The shaft is supported in spaced bearings 12-12, preferably formed integral with the bearing frame 13 which is secured to the base 2. Mounted fast on the shaft 10 is a barrel pinion 14 having a longitudinal slot 15 therein to register with the slot 11, the two parts 10 and 14 forming, in effect, a unitary structure. The bearing brackets 12-12 are slotted to register with the slots or grooves 11 and 15. A gear 16, which also constitutes a hand-wheel, meshes with the barrel pinion 14 and is mounted on a threaded shaft 17, the opposite ends of which are pinned to brackets secured to the bearing frame 13. This shaft carries check nuts or some equivalent means for adjustably limiting the axial travel of the gear 16 on the shaft 17, so that the twister head may be given a predetermined number of revolutions and then stopped automatically with 85 the slots 14 and 15 registering with the slots in the bracket 12.

For the purpose of holding the thread securely and at the same time avoiding any possibility of injuring even a delicate thread, the twister head is provided with two thread holding devices 20 and 21, one mounted at each end thereof. The thread holder 20 comprises a bracket 22, Fig. 4, which is pinned to the end of the shaft 10 and has a flat face flush with one wall of the slot 11. A plate 23 is set into this face and another plate or disk 24 is pressed lightly against it by a coiled spring 25 backed up by a nut 26 which is threaded on a post 27 projecting centrally through both the disks 23 and 24 and secured in the bracket 22. The other thread holding device 21 is a duplicate of that shown in Fig. 4. 100

In beginning the thread splicing operation, the thread *a* is led between the disks or plates of the thread holding device 21,

placed in the slot in the twister head A, and then given one turn around the pin or post 27 with the thread gripped between the plates 23 and 24. The end of this thread is 5 then placed in the clip 8. The thread *b* is placed in the twister head B in the same manner and its end secured in the clip 9. The gears or hand-wheels 16—16 for the 10 two twister heads are then rotated in the proper directions to untwist the two threads *a* and *b*, the check nuts being set properly to stop the rotation of the wheels, and consequently of the twister heads, when the twist has been completely taken out of the two 15 lengths of thread between said heads and their respective slips 8 and 9. While this operation is being performed the twist runs back into the lengths of threads between the twister heads and the spools. The provision 20 of a thread holding device at both ends of each twister head is of advantage in controlling the thread accurately and preventing its working out of the thread receiving slots where it might be caught and cut off. 25 Furthermore, the frictional type of thread holding device shown is well adapted to handle either fine or coarse threads, holding either kind securely and avoiding any possibility of injury to it.

30 After the threads have been untwisted, as just described, each thread is separated into its individual strands. The present invention provides an improved device for holding these separated strands. This device 35 comprises a tube 30 supported horizontally in front of, and between, the twister heads by means of rods 31—31, the front ends of which are secured in the tube while the rear ends are mounted in brackets supported under the base 2. Within the tube 30 are two 40 spiral springs 32 and 33, respectively, wound in opposite directions, the tube being partially cut away near opposite ends thereof, as clearly shown in Fig. 1, to expose portions 45 of the two springs. The adjacent ends of the springs are secured fast to the tube by screws 34 and 35, respectively. Referring to Fig. 3 it will be seen that the screw 34 passes through the eye of a screw eye 36, the shank of which is threaded into a disk or 50 plug 37 having pins projecting from its periphery and entered between adjacent coils at the right-hand end of the spring 32. The corresponding end of the other spring 33 is 55 similarly secured to the tube. The opposite end of the spring 32 is anchored in another plug 38 like the part 37, and a thumb screw 39, threaded axially through this plug, projects through the closed end of the tube 60 and affords a convenient means for adjusting the spring longitudinally. The other spring 33 is provided with a similar adjusting means, the adjusting screw therefor being designated at 40 in Fig. 1. This figure also 65 shows the three strands *b'* of the thread *b*

held between adjacent coils of the spring 33. This construction provides a very firm holding or gripping means for the strands, and the adjustability of the springs enables the operator to set it quickly and conveniently 70 for different gages or diameters of thread. The strands of the thread *a* are, of course, held by the coils of the spring 32.

After the strands have been separated in the manner just described, the individual 75 strands of the threads *a* and *b* are lightly twisted together and held against the yieldingly mounted plate 42, which is positioned between the twister heads, and the twister heads are then operated in the reverse direction 80 to that in which they were formerly rotated, thus twisting together the spliced strands as explained in detail in my prior patent.

The use of the right and left-hand wound 85 springs 32 and 33 instead of a single spring affords a more convenient and natural angle for the reception of the strands leading from the two twister heads. It is contemplated, however, that a single spring could be used 90 in place of the two springs shown. It will also be appreciated that the illustrated embodiment of the invention may be modified in other particulars without departing from the spirit or scope of the invention. 95

Having thus described my invention, what I desire to claim as new is:

1. In a thread splicing machine, the combination of two opposed twister heads mounted substantially in alinement with each other, each constructed to hold a thread and each rotatable in opposite directions to twist or untwist a thread, and a spiral spring mounted in front of said heads to hold the individual strands of untwisted thread. 100

2. In a thread splicing machine, the combination of two opposed twister heads mounted substantially in alinement with each other, each constructed to hold a thread and each rotatable in opposite directions to twist or untwist a thread, a spiral spring mounted in front of said heads to hold the individual strands of untwisted thread, and means for adjusting said spring longitudinally to vary the grip exerted by adjacent 110 coils thereof on a thread placed between them.

3. In a thread splicing machine, the combination of two opposed twister heads mounted substantially in alinement with each other, each constructed to hold a thread and each rotatable in opposite directions to twist or untwist a thread, and means in front of said heads for holding the strands of untwisted thread, said means comprising a tube, a spring in said tube, a portion of said tube being cut away to expose a part of the spring, and means for adjusting said spring longitudinally. 120

4. In a thread splicing machine, the com- 130

bination of two opposed twister heads mounted substantially in alinement with each other, each constructed to hold a thread and each rotatable in opposite directions to twist or untwist a thread, and means in front of said heads for holding the strands of untwisted thread, said means including a tube mounted substantially parallel to the axes of said twister heads, two spiral 10 springs mounted in said tube and having their adjacent ends anchored therein, said tube being partially cut away to expose portions of said springs, and screws connected with the opposite ends of the springs to 15 adjust the springs longitudinally.

5. In a thread splicing machine, the combination of two opposed twister heads, each grooved longitudinally to receive a thread, means rotatably supporting said heads and thread clamping devices mounted 20 at the opposite ends of each head, the thread clamping devices at the ends of said heads adjacent to each other each consisting of a plate rotating with the head, a disk bearing against said plate, a post fixed in the head 25 and projecting through said disk and on which the disk is movable toward and from the plate, and a spring pressing said disk against said plate.

ARTHUR A. BRIGHAM.
